UNITED STATES PATENT OFFICE.

DWIGHT B. HOLSON, OF LOS ANGELES, CALIFORNIA, ASSIGNOR OF ONE-HALF TO
ALBERT B. HOLSON, OF LOS ANGELES, CALIFORNIA.

FLYING MACHINE.

1,414,186.

Specification of Letters Patent. Patented Apr. 25, 1922.

Application filed July 21, 1919. Serial No. 312,371.

To all whom it may concern:

Be it known that I, DWIGHT B. HOLSON, a citizen of the United States, residing at Los Angeles, in the county of Los Angeles, 5 State of California, have invented new and useful Improvements in Flying Machines, of which the following is a specification.

This invention relates to flying machines and particularly to machines adapted to be 10 propelled vertically as well as horizontally. It is an object of the invention to provide a machine of this character which will be simple and efficient.

A particular object of the invention is to 15 provide a machine of this character which will be capable of being driven ahead, or horizontally, at the same time it is being suspended, or driven vertically. The means for driving or propelling the machine horizontally is independent of the means for suspending or propelling it vertically, and the 20 means for propelling it vertically is adjustable—that is—it may be set so as to help to propel the machine horizontally as well as to 25 propel it vertically. This independence of horizontal and vertical propelling means and the adjustability of the vertical propelling means allows the machine to be controlled or manoeuvered very easily. The machine being 30 easily controlled and capable of being propelled vertically makes it require only a small space on which to land. This fact makes the machine particularly adapted for use in large cities where large landing spaces 35 are not available. Another feature of the invention which makes it of great commercial value is the high speed at which it may be driven. The machine may be propelled at a very high speed when the vertical propelling means is adjusted or set in such a 40 manner as to propel the machine horizontally and thereby assist the horizontal propelling means.

A further and particular object of the invention is to provide a light, simple and 45 highly efficient vertical propelling mechanism. The invention provides a mechanism whereby a high speed internal combustion engine may be used to drive a plurality of 50 propellers. The mechanism allows a speed reduction to be made between the engine and the propellers, which speed reduction may be made to suit various conditions, but it is preferred that the reduction is such as

to allow the engine to run at its most efficient 55 speed and also cause the propellers to be driven at their most efficient speed. The lightness of the mechanism which effects these results is a particular feature of the invention. Although the mechanism is light 60 and simple, it is so arranged as to be particularly strong and durable. Due to the simplicity of the mechanism and its novel arrangement, high mechanical efficiency is attained. The efficiency thus attained in the 65 vertical propelling mechanism adds greatly to the ultimate efficiency of the entire machine.

Other objects and features of the invention will be readily understood from the 70 following detailed description of a preferred form of the invention throughout which reference is had to the accompanying drawing, in which—

Fig. 1 is a plan view of the machine showing the arrangement of the horizontal driving means and also the vertical driving means; Fig. 2 is an enlarged detail section taken as indicated by line 2—2 on Fig. 1 and shows the arrangement of the vertical driving mechanism control lever; Fig. 3 is an enlarged detail section taken as indicated by 80 line 3—3 on Fig. 1; Fig. 4 is an enlarged detail section taken as indicated by line 4—4 on Fig. 1; and Fig. 5 is a plan view of the 85 parts shown in Fig. 3, and is taken as indicated by line 5—5 on Fig. 3.

In the drawings numeral 10 designates the fuselage or body of the machine to which are attached the wings 11. Although the body 90 10 may be made in various forms or shapes it is preferred that it be made substantially in the shape of a torpedo, and that the occupant's seat be placed in the forward end of the body. Mounted at the rear end of the 95 body 10 there may be elevators 13 and a rudder 14. The rudder 14 controls the direction in which the machine is travelling and the elevator 13 controls its height when it is being driven in a horizontal plane only. The 100 wings 11 are preferably shaped as shown in Fig. 1, and are adapted to support the machine when it is travelling horizontally only. The machine is provided with two propellers 15 which are adapted to propel it horizontally. The propellers 15 comprise blades 16 mounted on rings 17. The rings 17 are provided with teeth and form ring gears which 105

are driven by pinions 18 mounted on the shaft of engine 19. The engine 19 is preferably an ordinary internal combustion engine and is arranged to drive both of the 5 rings 17 as shown in Fig. 1. The speed reduction between the engine and the propellers is preferably such as to allow a high speed powerful engine to be used in this connection. This arrangement is substantially the same as that shown in Patent No. 10,001,956, dated Aug. 29, 1911.

Mounted transversely in the body 10 there is an engine 20 which drives drive-shafts 21. The drive shafts 21 are preferably directly 15 connected to the engine shaft and extend from both sides of the engine 20. They are carried in housings 22 which are preferably made of thin light metal and extend from the engine 20 to the wings 11 as shown in 20 Fig. 1. Portions 23 of the engine 20 are preferably made to form bearings for one end of the housings, while the other ends are supported by bearings 24 on the under side of the wings 11. The housings 22 25 are carried in the portions 23 and the bearings 24 so that they may be rotated as will be hereinafter described. Carried by each housing 22 between the engine and the wing there is a propeller 25. Each propeller 25 comprises blades 26 which are mounted on a ring gear 27. There may be any suitable number of blades 26 mounted on the ring gear 27 and said blades may be shaped and set in such a manner as to drive 30 the machine most effectively. The ring gear 27 is preferably of considerable diameter and has gear teeth 28 on both sides or faces as shown in the drawings. The ring gear 27 is driven by pinions 30 which are mounted 35 on drive shaft 21. The ring gear 27 is tilted or set at such an angle as to allow one of the pinions 30 to engage one face of the ring gear 27 while the other pinion 30 engages the other face, as shown in Fig. 4. This 40 arrangement causes both the pinions 30 to drive the ring gear 27 in the same direction and causes the driving strain to be divided between the pinions 30 rather than be concentrated on a single pinion. The dividing 45 of the driving strain between the two pinions 30 causes a distribution of strains in the ring gear and thereby prevents twisting or warping of said gear. The fact that the ring gear 27 does not have a tendency to 50 twist or warp allows it to run true and thereby allows the pinions 30 to properly and accurately engage the teeth 28. The proper engagement of the pinions 30 and the teeth 28 decreases friction due to improper mesh- 55 ing of the gear teeth, thereby causing the efficiency of the drive to be very high. Another very important feature which accompanies this arrangement is the durability of 60 the gears. Due to the proper alignment of the pinion 30 and the gear 27 and the dis-

tribution of the driving strains between the two pinions, the wear on the teeth of the pinions and the gear is very slight. This slight wear between the pinions and the gear not only makes the life of the mechanism 70 long but also allows it to be operated for a long time without resetting or lining the gear and pinions. Although a single propeller 25 has been shown and described in connection with each drive shaft 21, it will be understood that several propellers may be arranged in connection with each shaft if so desired.

The engine 20 is preferably a high speed powerful engine and the speed reduction between the pinions 30 and the gear 27 is preferably sufficient to cause the propeller 25 to be driven at its most effective speed. It will be readily understood that by varying the size of the pinions or by varying the diameter of the gear that the speed reduction can be easily changed.

Near each pinion 30 there is a bearing casting 40 which supports drive shaft 21. Each casting 40 is mounted in an enlarged 90 portion 41 of the housing 22. Extending from the inside or inner edge of ring 27 there is a rib or flange 43. Mounted on the shaft 21 between the casting 40 and the pinion 30 there is a roller 44 which engages 95 one side of flange 43, as shown in Fig. 3. Pivottally mounted in the casting there are two rollers 45 which engage the other side of flange 43 and pivotally mounted in the same casting there is a roller 47 which engages 100 the inner periphery of flange 43. It will be readily seen how this engagement of the flange 43 by the rollers 44, 45 and 47 firmly supports the ring gear 27 in position, and it will be noted that the gear 27 is supported at the point where it is in engagement with pinion 30. The particular feature of this construction is the elimination of parts such as spokes, hubs, bearings, etc. This manner of supporting the gear 27 eliminates 105 parts and thereby makes the mechanism simple and extremely light. The lightness of construction is a very important feature as lightness of construction in heavier than air machines is very essential. It will be noted 110 that the rollers 45 are spaced some distance apart and that they are mounted in the casting 40 which is mounted on the housing 22. By this arrangement it will be readily understood that rotation of housing 22 will 115 cause tilting of ring gear 27. It is by rotation of housings 22 that it is possible to tilt or turn the propellers 25 so as to be in the same plane as the propellers 15 and thereby assist propellers 15 in driving the machine 120 horizontally. It will be understood, however, that it is not necessary to tilt the propellers 25 until they are in the same plane with propellers 15, but they may be tilted to any desirable angle or plane between 125 130

the horizontal and the vertical plane. Any suitable mechanism may be used in connection with housings 22 in order to rotate them. For instance, a lever arm 50 may be mounted on each housing to which may be connected a control rod 51. The control rods 51 may be arranged so as to extend to the operator's seat 12 where they may be connected to independent levers 54. This arrangement provides a simple and effective control by which the housings 22 may be independently adjusted.

It will be readily understood from the foregoing description of the construction of the machine how it may be controlled and operated. Upon leaving the ground and upon alighting it is preferred to use only the vertical propellers, as the machine may be raised or lowered by varying the speed of rotation of the propellers 25. For instance, when it is desired to descend, the speed of the propellers 25 may be reduced until their effect is not sufficient to drive the machine upwardly. When the machine has reached a sufficient altitude, and it is desired to drive it horizontally only, the vertical propellers 25 may be tilted by the mechanism hereinabove described so that they are in the same plane and thereby assist as the propellers 15. When the machine is set in this manner—that is, when all of the propellers are tending to drive it horizontally, a very high speed may be attained. It will be noted that the propellers 25 are provided with independent tilting mechanisms, thereby making it possible to adjust said propellers independently.

Having shown and described a preferred form in which the invention may be embodied, I do not wish to limit myself to the particular details hereinabove set forth but wish to reserve to myself any changes or modifications that may appear to those skilled in the art which may fall in the scope of the following claims.

Having described a preferred form of invention, I claim:

1. In a flying machine, propelling means comprising an annular member having blades extending from it and having gear teeth on two faces, a drive shaft, two pinions mounted on the shaft adapted to engage the teeth on opposite faces of said annular portion, and driving means for said shaft.

2. In a flying machine, propelling means comprising an annular member having blades extending from it and having gear teeth on two faces, a drive shaft, two pinions mounted on the shaft adapted to engage the teeth on opposite faces of said annular member, driving means for said shaft, and supporting means for said annular member near its points of contact with said pinions.

3. In a flying machine, propelling means comprising an annular member having

blades extending from it and having gear teeth on two opposite faces, a drive shaft, two pinions mounted on the shaft adapted to engage the teeth on opposite faces of said annular member, and a shaft housing carrying supporting means for said shaft and said annular member, there being supporting means near each pinion.

4. In a flying machine, propelling means comprising an annular member having blades extending from it and having gear teeth on two opposite faces, a drive shaft, two pinions mounted on the shaft adapted to engage the teeth on opposite faces of said annular member, and a rotatable housing carrying supporting means for said shaft and said annular member, there being supporting means near each pinion.

5. In a flying machine, propelling means comprising an annular member having blades extending from it and having gear teeth on two opposite faces, a flange on the annular member, a drive shaft, two pinions mounted on the shaft adapted to engage the teeth on opposite faces of said annular member, and supporting means for said annular member, said means comprising a roller adapted to engage the inner periphery of said flange, a roller adapted to engage one side of said flange and a roller adapted to engage the other side of said flange.

6. In a flying machine, propelling means comprising an annular member having blades extending from it and having gear teeth on two opposite faces, a flange on the annular member, a drive shaft, two pinions mounted on the shaft adapted to engage the teeth on opposite faces of said annular member, and supporting means for said annular member, said means comprising a roller adapted to engage the inner periphery of said flange, a roller adapted to engage one side of said flange, and a plurality of rollers adapted to engage the other side of said flange at circumferentially spaced points.

7. In a flying machine, propelling means comprising an annular member having blades extending from it and having gear teeth on two opposite faces, a flange on the annular member, a drive shaft, two pinions mounted on the shaft adapted to engage the teeth on opposite faces of said annular member, and a rotatable shaft housing, supporting means for said annular member carried by the housing, said means comprising a roller adapted to engage the inner periphery of said flange, a roller adapted to engage one side of said flange, and a plurality of rollers adapted to engage the other side of said flange at circumferentially spaced points, said supporting means causing tilting of said annular member when said housing is rotated.

8. In a flying machine, propelling means

- comprising, an annular member having blades extending from it and having gear teeth on opposite faces, a drive shaft, pinions mounted on the shaft adapted to engage 5 the teeth on opposite faces of said annular member, a rotatable housing for the shaft, and means carried by the housing to support the annular member and to cause tilting of the annular member when the housing is 10 rotated.
9. In a flying machine, propelling means comprising, an annular member having blades extending from it and having gear teeth on opposite faces, a drive shaft, pinions 15 mounted on the shaft adapted to engage the teeth on opposite faces of said annular member, a rotatable housing for the shaft, and means carried by the housing at the pinions to support the annular member and to 20 cause tilting of the annular member when the housing is rotated.
10. In a flying machine propelling means comprising, a shaft, means for driving the shaft, and an annular member arranged on 25 the shaft to be driven by the shaft at two spaced points, the annular member having blades extending from it and having its axis at substantially right angles to the axis of the shaft.
- 30 11. In a flying machine, propelling means comprising, a shaft, means for driving the shaft, and an annular member arranged on the shaft to be driven by the shaft at two diametrically opposite points, the annular 35 member having blades extending from it and

having its axis at substantially right angles to the axis of the shaft.

12. In a flying machine, propelling means comprising, a shaft, pinions mounted on the shaft, means for driving the shaft, and an 40 annular member, with blades extending from it and gear teeth on two faces, arranged on the shaft so that the gear teeth on each face are engaged by a pinion and so that the points of engagement between the 45 pinions and the gear teeth are diametrically opposite.

13. In a flying machine propelling means comprising, a shaft, means for driving the shaft, pinions mounted on the shaft, a plurality of annular members having gear teeth on two faces and having blades extending from them, a plurality of housings rotatably carried on the shaft and means carried by each housing to support one of said members so that the gear teeth on each of its faces are engaged by a pinion and so that the points of engagement between the pinions and the gear teeth are diametrically opposite, each annular member having its axis at 55 substantially right angles to the axis of the shaft and being adapted to tilt on the shaft upon rotation of its housing.

In witness that I claim the foregoing I have hereunto subscribed my name this 14th 65 day of July 1919.

DWIGHT B. HOLSON.

Witness:

VIRGINIA I. BINGER.
